UNITED STATES PATENT OFFICE.

JOHN J. JENSEN, OF MELHAM, SOUTH DAKOTA, ASSIGNOR OF ONE-HALF TO WILLIAM B. STRICHERZ, OF MELHAM, SOUTH DAKOTA.

PLOWPOINT.

Application filed April 4, 1923. Serial No. 629,892.

To all whom it may concern:

Be it known that I, JOHN J. JENSEN, a citizen of the United States, residing at Melham, in the county of Clark and State 5 of South Dakota, have invented new and useful Improvements in Plowpoints, of which the following is a specification.

This invention relates to plows and has for its object the provision of a removable 10 or attachable point which may be applied to a worn plow whereby to restore it to thoroughly efficient condition.

An important and more specific object is the provision of a point of this character 15 which is designed to be welded onto a worn plow, the arrangement being such that the usual scar will be entirely or almost entirely eliminated.

It is well known that the ordinary soft 20 point plow lay is constructed in one piece of soft center steel welded to a softer piece of material which constitutes the landside. When the average plowshare has been used for plowing 20 to 30 acres the natural wear 25 comes on the underside of the landside with practically nothing but the thin slab of soft center steel to resist the wear. In most cases a farmer uses the old lay as long as possible and that of course shortens the landside before any other part of the lay, because 30 most of the work of the lay is done at the point.

It is with these facts in view that I have 35 designed the present attachable point, which being constructed of very rough hard steel will outwear any ordinary point and give the maximum durability and length of life together with efficient service.

With the above and other objects and ad- 40 vantages in view the invention consists in the details of construction to be hereinafter more fully described and claimed and il- lustrated in the accompanying drawings, in 45 which:

Figure 1 is a perspective view of my point,

Figure 2 is a view thereof showing the method of attaching it to a worn plow,

Fig. 3 is a side elevation showing the 50 point in applied position,

Fig. 4 is a side elevation partly in longi- 55 tudinal section,

Fig. 5 is a perspective view of the device taken from a different angle from that dis- 60 closed in Fig. 1, and

Fig. 6 is a detail view looking at the rear end.

Referring more particularly to the drawings I have shown my point as comprising a single body 10 which may be constructed as 60 a casting, forging or which may be formed in any other desired or preferred manner such as by pressing. It is intended that these points be made at some suitable factory for distribution to customers, blacksmiths or 65 others engaged in the use of plows or in the repairing thereof. This body is naturally of a rather peculiar shape and includes a thickened bottom or landside portion 11 and a transverse and longitudinally curved 70 share portion 12 which has its forward edge inclined as at 13 and which has its rear end formed with a rearwardly extending wing 14. One side of this body is hollowed out 75 as indicated at 15.

In applying the point, only two welds are required. The landside and forward end of the share of the worn plow are brought into proper relation to the body 10 and the landside is welded first, any suitable weld- 80 ing compound being used. The lay is then turned over and the throat is welded by a trip hammer or other method of hammering to draw out the throat which is necessary 85 to give the lay a good suck and an even cutting edge. The landside being welded and the throat drawn out leaves an unequal or irregular shape plowshare free from the bad scar which is present on top of the lay in old style plow points. The purpose of 90 having this point pressed or forged hollow at the bottom side is to allow the frog of the plow to protrude under the same to give a perfect bearing for the plow lay. It might 95 be mentioned that the lines of welding are indicated on the drawing by the numerals 16 and 17.

From the foregoing description and a 100 study of the drawing it will be apparent that I have thus provided a simply applied and highly efficient plow point which will have the maximum durability and which will be a great improvement in every way.

While I have shown and described the 105 preferred embodiment of the invention it is of course to be understood that I reserve the right to make such changes in the form, construction and arrangement of parts as will not depart from the spirit of the invention or the scope of the subjoined claims. 110

Having thus described my invention I claim:

1. An attachable plow point consisting of an elongated body formed as a single piece of material, including a relatively thick landside having its rear edge tapered, further including a share portion curved longitudinally and transversely and having an inclined forward end, said body being adapted to be welded onto a plow lay and being formed with a hollowed out portion to receive the frog.
2. An attachable plow point consisting of an elongated body formed as a single piece of material, including a relatively thick landside having its rear edge tapered, further including a share portion curved longitudinally and transversely and having an inclined forward end, said body being adapted to be welded onto a plow lay and being

formed with a hollowed out portion on its under side to receive the frog, said share portion of the point lying exteriorly upon and being welded to the lay along a curved line, and said share portion being formed with a relatively narrow rearwardly extending wing.

3. An attachable plow point comprising an elongated body having a relative thick intermediate portion and tapered to an obliquely extending forward edge, the rear end of the body being formed with a tapered extension and a divergent share portion, said rear end of the body being forked for the reception of the point of a plowshare and the intermediate and forward portion of the body being recessed on its underside for the reception of the frog of a plow.

In testimony whereof I affix my signature
JOHN J. JENSEN.
